UNITED STATES PATENT OFFICE.

LOUIS A. M. PHELAN, OF BELOIT, WISCONSIN, ASSIGNEE, BY DIRECT AND MESNE ASSIGNMENTS, OF ONE-HALF TO ABSOLUTE CON-TAC-TOR CORPORATION, A CORPORATION OF ILLINOIS, AND ONE-HALF TO ARCLESS CONTACT COMPANY, OF CHICAGO, ILLINOIS, A CORPORATION OF ILLINOIS.

ELECTRICAL APPARATUS.

Application filed January 19, 1922. Serial No. 530,243.

My invention relates to electrical apparatus and it has special reference to improvements in electrical contact-making devices wherein the conducting terminals or electrodes, at which the electrical contact-making and breaking operations are effected, are enclosed in a container which also contains a compact and coherent body of current-conducting fluid, through the agency of which the said electrodes are brought into electrical conducting relation with one another.

My present invention refers particularly to electrical contact-making or electrical switching devices of the character indicated above which are adapted for commercial operations and to meet the requisite service conditions as to current-carrying capacities, voltages, life, reliability, etc., as distinguished from prior contacting devices for use in the laboratory or experimental work that comprise a container having electrodes sealed therein and a body of mercury which, on tilting or actuating the container in proper fashion, serves to establish an electrical circuit between the said electrodes.

The object of my present invention is to provide a device, as mentioned above, which is capable of opening and closing an electrical circuit an extraordinarily large number of times, as compared with the contacting devices of the prior art, without undergoing substantial deterioration and while operating under service conditions, such as current and voltage requirements, dependability and life, that are required of electrical apparatus in commercial installations.

Another object of my invention is to provide an electrical switching device or contactor comprising a body of mercury for bridging gaps between electrodes sealed in a suitable container and which will be economical to construct and will operate with dependable reliability on commercial voltages and serve to open and close electrical circuits carrying currents of substantial values, such as are encountered in commercial installations.

Moreover, my contacting device is capable of being operated with a minimum expenditure of energy and on circuits handling substantial quantities of current because it readily dissipates the heat generated by the making and breaking of the electric circuit.

Other advantages of my present invention will be hereinafter pointed out and described.

I am aware that it has heretofore been proposed to employ contact-making devices comprising a closed container in which electrodes were sealed that, at proper times, were brought into electrical conducting relation with one another through the agency of a body of mercury likewise contained in the container. The containers of these proposed devices have sometimes been evacuated and sometimes filled with so-called inert gas, such as nitrogen, but I am not aware that any such devices have ever been used commercially for the handling of any substantial quantities of electrical current at the usual voltages, or been embodied in commercial installations wherein the devices would be subjected to substantial voltages and currents and possess a suitably long life thereby making such devices dependable or even technically successful.

In the devices, heretofore used and of this general character, ordinary mercury has been employed for closing and opening the electrical circuits between the electrodes. The electrodes in such prior devices have been made of metals of the usual commercial purity and have been disposed in glass containers. The leading-in wires of such prior devices, which leading-in wires did not provide substantially permanent hermetic seals in the walls of the container and particularly when the leading-in wires were of sufficient size to conduct commercial quantities of electric current, have caused rapid deterioration of the devices since they have been exposed within the interior of the sealed containers and when nitrogen or the other gases heretofore used have been employed to fill the containers, such prior contactors soon become inoperative when subjected to electrical currents of any substantial value because of the fact that deposits would form on the interior surfaces of the containers and, in time, would short-circuit the electrodes or a conducting scum would bridge the electrodes or form a slag or film between the electrodes and thereby short-circuit them. From my extensive experience with such contactor devices filled with nitrogen and other so-called inert gases of the prior art, I have found that even when the

2

materials entering into their construction possess a high degree of purity, the nitrogen or other so-called inert gases would react chemically with the mercury or the electrodes, thereby forming in the event of nitrogen being used, a compound of nitrogen and mercury which deposited on the inner surfaces of the container. These deposits destroy the dependency and life of the contactor device by reason of such deterioration. Prior contactor devices of this general character when employed commercially have been used only in connection with relays and, of themselves, were not capable of handling any substantial quantity of electrical current throughout a commercially successful life. I am not aware that such contacting devices as the prior art discloses, were employed successfully in any commercial installations to open and close electrical power circuits where the devices were subjected to operating conditions that required the making and breaking of electrical currents of any substantial value throughout a commercially successful life.

Contactors constructed in accordance with my present invention have been extraordinarily successful as to their life, when subjected to the voltages and current obtaining in commercial installations and, moreover, I am usually able to dispense with relay circuits since my present contactor, of itself, may handle the requisite electrical currents and voltages of power circuits.

35 For a better understanding of my invention, reference may be had to the accompanying drawing, in which—

Figure 1 is an enlarged view, partially in section, of a contactor embodying a form of my invention, and

Fig. 2 is a view showing the device of Fig. 1 in circuit-closing position.

The contactor comprises a container 1, such as a glass tube, in which two spaced electrodes 2 and 3 are sealed. I have shown the electrodes 2 and 3 as being disposed at right angles to each other and as closely abutting glass shanks 4 and 5 respectively. But I am not limiting my invention to such a mechanical structure. The leading-in wires 6 and 7 provide means for electrically connecting the electrodes 2 and 3 to their respective accessible terminals 8 and 9. In the specific embodiment of my invention shown and described herein, the leading-in wires 6 and 7, that are capable of handling commercial quantities of current, are made preferably of dumet wire which comprises a nickle-iron alloy and insures substantially permanent hermetic seals in the glass container 1 when the seals become heated or when substantially high currents traverse the leading-in wires. It is to be understood that I am not to be limited to any specific leading-in wires, since any material for this

purpose will be satisfactory as long as substantially permanent hermetic seals in the container 1 are obtained and providing that the leading-in wires are either of such material as will not cause deterioration of the contactor or are precluded from being exposed within the container 1, as I have herein described. In the specific embodiment of my invention, the leading-in wires 6 and 7, when made of dumet wire, have no portions exposed in the interior of the glass container 1 since, after their entry into the walls of the glass container 1, they are completely embedded in glass. The electrodes 2 and 3 are welded or secured to their respective leading-in wires in any suitable fashion. The only metal exposed to the interior of the container 1 is that of which the electrodes 2 and 3 are made or a metal which is permanently non-deteriorating under the conditions obtaining within the container. The air contents of the container 1 are evacuated to a suitably high degree and the container 1 is then filled with an inert gas, such as will be hereinafter described. A freely movable meniscus of mercury 10 is also disposed within the container 1 and this body of mercury serves to make and break the electrical circuit between the electrodes 2 and 3, as the container 1 is tilted or actuated as shown in Fig. 2. Any suitable means may serve to tilt the container 1 so as to make and break the electrical circuit between the electrodes 2 and 3 through the agency of the body of mercury 10.

The glass container 1 which I have illustrated in the contactor of the drawing is made from the quality of glass that is employed for manufacturing bulbs for incandescent lamps. The electrodes 2 and 3 are made from pure metals which are substantially devoid of any impurities. In some instances I construct the electrodes 2 and 3 of substantially pure iron. I also find that pure nickle is very satisfactory under certain conditions and, of course, tungsten of the purity employed in incandescent lamps may also suffice for some classes of service. It is necessary that neither the metals from which the electrodes are constructed nor the impurities obtaining in these metals enter into chemical combination with either the mercury or the inert gas which I fill into the container 1, even under the influence of electric arcs which are occasioned at all times with varying degrees of intensity as the electrical circuit is opened and closed between the electrodes. I have mentioned herein that the electrodes 2 and 3 may be made of metals that are substantially non-amalgamating under the conditions obtaining in my electric switch and, in some instances, I refer to such metals as being of the iron group, such as iron, nickel and tungsten and, therefore, by the term "iron group", as em-

ployed herein, I mean metals of the aforesaid character.

The mercury which I embody in my contactor should likewise be of unusual purity.

5 I find that it is very desirable for the mercury to be of a high degree of purity, since ordinary mercury or mercury which is usually designated commercially as chemically pure mercury is worse than useless for a contactor of any substantial life and adapted to operate on a power circuit.

10 I evacuate the container 1 to a suitable commercial vacuum which I have determined by experience and experiment to be satisfactory. After the container has been evacuated, I fill it with a gas which, in this instance, I will designate as an inert gas. For the particular combination and relation in which this gas is employed in my 15 contactor, as well as the electrical and heat conditions obtaining when my electric switch is subjected to operating conditions, it is inert, as this term is defined herein. I have found that by filling hydrogen into 20 the container 1, which is preferably filled with this inert gas to a pressure of substantially one atmosphere, I am able to secure the highly satisfactory results such as I have outlined above, in connection with electrical 25 service conditions to which my contactor tubes are particularly adapted. I have found that hydrogen is permanently inert to the materials entering into the construction of my contactor tube, even in the presence of substantial electric arcs which are 30 of frequent occurrence when the contactor tube is submitted to operating conditions. I have found that hydrogen, as the inert 35 gas, minimizes the intensity of the arcing which takes place at the electrodes, and particularly at the electrode 2 as the circuit is established and broken when the body of mercury 10 approaches and recedes from the electrode 2. Hydrogen, by reason of its in- 40 ertness, also precludes the pitting of the electrodes 2 and 3 and I have found that with my contactor tubes which have been in operation for a considerable period of time on circuits handling electrical currents 45 of substantial values which have been broken a great many thousands of times are not pitted and show no deterioration whatever even under a very high powered microscope. This, of course, is an extraordinary 50 accomplishment, namely that the electrodes remain intact even though they have been subjected to electric arcs of considerable intensity and a very great number of times.

55 I have found that the minimizing of the intensity of the arcing or, rather the arc-suppressing property of hydrogen gas and the absence of pitting and disintegration of the electrodes 2 and 3, referred to above, is brought about by reason of the fact that 60 mercury, in the presence of hydrogen, when

an arc is established at the iron electrodes "wets" the said electrodes. After a few makes-and-breaks of the electric current flow through the contactor device, a film of mercury permanently adheres to the electrodes 70 2 and 3 thereby "wetting" them. By reason of this mercury film formed on the contact making surfaces of the electrodes 2 and 3, the electric arcing is suppressed or substantially minimized as the body of mercury 75 makes and breaks the electric circuit between the electrodes. In this manner, arcing at the electrodes is substantially minimized and the electrodes 2 and 3 are protected against pitting and the consequent 80 disintegration because the electric arcs are established and broken between the films of mercury wetting the electrodes 2 and 3 and the meniscus of mercury 10. For this reason, vaporization of the materials within the 85 contactor is minimized except for the vaporization of the mercury and, therefore, no deposits are formed on the interior walls of the tube. I have discovered that iron possesses, to a highly marked degree, this 90 aforementioned property of permitting a film of mercury to adhere to it in the presence of hydrogen gas, this condition obtaining throughout the life of the contactor tube and even when subjected to excessively high 95 currents. If hydrogen gas is replaced by carbon dioxide or nitrogen or other so-called neutral inert gases, I have found that the electrodes 2 and 3 do not become "wetted" by the mercury. As a result, the electrical 100 arcs instead of occurring between the body of mercury 10 and the mercury films adhering to the electrodes 2 and 3, as occurs when electrodes of suitable metal are employed in the presence of the hydrogen gas, the arcs 105 will occur between the body of mercury 10 and dry electrodes which will cause the electrodes to become pitted, thus enhancing their disintegration with the consequent forming of a conducting scum which may 110 deposit on the interior walls of the contactor or otherwise affect its operation. Moreover, the arcing will not be suppressed and, consequently, further disintegration of the electrodes is effected, as well as the generation of large quantities of heat that is 115 difficult to dissipate properly without destroying the glass tube or the seals for the leading-in wires 6 and 7.

120 It will be observed that the electrodes 2 and 3 are of substantial concentrated mass in order to have sufficient heat absorptive capacity and that their contacting surfaces are substantially large in area in order that mercury films of appreciable surface area 125 may form upon them. I cannot explain the exact conditions that obtain within my contactor device which cause the mercury films to adhere to the surfaces of the electrodes 2 and 3, but I find that after an electric cir- 130

cuit has been made and broken several times between the electrodes 2 and 3 and the body of mercury 10, films of mercury are formed upon the exposed surfaces of the electrodes 5 and permanently adhere thereto. Sometimes these films are very thin and hardly discernible with the naked eye, but their existence is accounted for by reason of the lack of deterioration of the electrodes. The 10 make-and-breaks of the electric current, on subsequent actuations of my contactor device, are thereby effected always between the body of mercury 10 and the mercury films adhering to the electrodes 2 and 3.

15 The atmosphere of hydrogen contained within the contactor does not react chemically with the other materials which are exposed thereto and, consequently, no deposits are formed on the interior walls of the 20 container even after the contactor has been in operation for a very considerable period of time. The hydrogen gas appears to suppress the arcs obtaining at the electrodes 2 and 3 and, in addition to this function, the 25 hydrogen serves as a reducing agent for any of the water-vapor that may be contained within the tube, as well as any of the occluded gases that may be absorbed by the glass or the materials comprising the container 30 and the electrodes.

I have discovered that hydrogen imparts desirable properties to my contactor device after extensive experiments and contrary to the usual theory concerning the inertness or 35 the arc-suppressing property of hydrogen. Again hydrogen, by reason of its molecular mobility, serves to transfer at a very high rate the heat that is developed by the arcing to the walls of the container 1. I am quite 40 aware that hydrogen has been used in connection with the well known ballast resistors of Nernst lamps but this, of course, is not an equivalent use of hydrogen in electrical switching devices, such as my present contactor.

In filling the container 1 with hydrogen, or any other suitable inert gas possessing properties similar to those of hydrogen, the inert gas is preferably at a pressure of substantially 50 one atmosphere in order to minimize the difference of pressures obtaining at the seals both exteriorly and interiorly of the container 1, but it will be apparent that other pressures as long as not below arc 55 suppressing pressure, may be entirely suitable depending upon the operating conditions. The hydrogen which I use is in a high degree of purity. Of course, it will be obvious that I may employ other inert gases, 60 for instance, helium may be substituted for the hydrogen. At the present time, however, the employment of this latter gas is out of the question in view of the expense of producing it in commercial quantities and 65 in the desired high state of purity. In the

employment of hydrogen as the inert gas in my contactor, I realize that it is done in direct contradiction to the usual practice and to the dictates of chemistry. Apparently it is the physical action of the hydrogen 70 or other inert gas and the chemical inertness which assists in the production of the electrical contactor of my present invention.

To secure satisfactory results, the gases and materials entering into the construction 75 of my contactor devices should be of substantial purity, such as is required of materials entering into the construction of high-powered gas-filled incandescent lamps.

While I have described but one embodiment of my invention it is obviously not limited to the particular apparatus here described but I contemplate the use of such a combination of conducting and insulating fluid in other connections employing 85 electric arcs. This is especially true where devices are employed wherein a conducting agent is placed which may be volatilized by the passage of electrical current; in other words, I believe that it is entirely novel to 90 position within a contactor containing mercury, or analogous conducting fluids, a gas having such characteristics that although it would seem to explode under the influence of an electric current or an electric arc, 95 it does not and, moreover, it performs the desirable function of preventing chemical or physical reactions or combinations within the contactor which are conducive to deterioration thereby resulting in the failure 100 of such devices.

When the conducting agent or mercury 10 is substantially chemically pure so as to cleanse it of any foreign substance which may impair the operating qualities or the 105 life of the contactor, I have found that nitrogen as the alleged inert gas, is very unsatisfactory because a chemical reaction between mercury and nitrogen obtains which results in the depositing of an electrical conducting coating on the interior surface of the contactor and between the electrodes thus establishing an electrical by-pass between them. With the use of hydrogen this condition is eliminated and I am thus 110 able to procure contactors which have an almost indefinite life, even when subjected to severe operating conditions and which are suitable for commercial operations and more dependable than other electrical apparatus employed in commercial electrical switching devices.

The leading-in wires 6 and 7 are made of dumet wire which is the most satisfactory material to use commercially in connection 115 with hermetically sealed glass containers. Dumet wire has an exterior copper coating over a nickel-iron alloy wire and, as a consequence thereof, it is essential to prevent exposure of the leading-in wires in the in- 120 130

terior of the container 1, since copper under certain conditions may cause deterioration. To preclude the exposure of the copper coating of the leading-in wires 6 and 7, I have embedded them in the glass shanks 4 and 5. The leading-in wires 6 and 7, in lieu of being protected by the glass shanks 4 and 5, may be coated with platinum or pure iron which I have ascertained do not affect my contactor tube or cause it to deteriorate. However, it would be expensive to thus coat the leading-in wires 6 and 7 with inert metals and particularly platinum and, for this reason, I employ the glass shanks 4 and 5.

It is to be observed that the electrodes are adjacent to each other and at one end of the container, that the electric make-and-break is established and broken at the electrodes 2 and 3, that the container is in the form of an elongated cylinder, and that the freely movable meniscus of mercury 10 rides longitudinally of the cylindrical walls of the container with minimum frictional resistance and out of engagement with any thing except the smooth inner wall of the glass container. This is highly important in order that my contactor tube may be tilted or actuated with a minimum expenditure of energy and through a minimum tilting angle. It is apparent that each time the circuit is closed, the body of mercury 10 is moved into a position approximating that of Fig. 2, and when the circuit is opened, the body of mercury occupies a position approximating that shown in Fig. 1. Now, in order to move the mercury into circuit-closing and circuit-opening positions, the container 1 must be tilted. This tilting operation should be effected with a minimum expenditure of energy and through a minimum angular displacement, such as is capable of being generated through the agency of a thermostatic element. I have found, by constructing the container 1 as shown and described herein, the body of mercury 10 may be moved at the expense of very little energy. This is accomplished by balancing my contactor about its middle portion so that by a slight tilting action in either direction the body of mercury may be moved correspondingly to effect the proper circuit connections or disconnections.

The meniscus of mercury 10 is a body which coalesces as a unit mass when the container 1 is tilted in either direction. When the container 1 occupies the position shown in Fig. 1, it will be noted that the mercury meniscus 10 is moved away from proximity of the electrodes 2 and 3 and occupies a position under the glass supporting shank 5. In the open circuit position of the contactor, the mercury meniscus 10 is, therefore, moved away from the electrodes 2 and 3 thereby maintaining the high insulating

value of the space between the two cooperating electrodes. If the meniscus of mercury 10 occupied a position immediately under the electrodes 2 and 3 in open circuit position of the contactor, the insulating property of the contactor would be substantially minimized since both electrodes 2 and 3 would then be in close electrical relation to each other through the body of mercury 10 which, of itself, is a conducting medium. When the mercury meniscus 10 is in open circuit position, as shown in Fig. 1, the voltage applied to the electrodes 2 and 3 may be of a substantially high value such as obtains on commercial power circuits. As a result, my contactor device furnishes adequate insulating strength to the two sides of the circuit in which the contactor may be connected.

By tilting the contactor through a minimum angle, such as shown in Fig. 2, the meniscus of mercury 10 is then moved to such a position that the space between the electrodes 2 and 3 is bridged by the mercury thereby bringing these two electrodes into electrical conducting relation.

It will be observed that the electrode 2 is rounded off bluntly in order that the mercury meniscus 10, when receding from it as the switch moves to open circuit position, may move with a minimum sticking action between the electrode 2 and the mercury. This allows the mercury to be moved to open circuit position with a minimum tilting action of the switch.

The electrodes 2 and 3 are located centrally of the axis of the container and above its lower wall thus permitting the freely movable meniscus of mercury 10 to slide unobstructedly on the lower inner surface of the container 1. As a result, the body of mercury 10 is capable of moving out of proximity to the electrodes 2 and 3 when the switch is in open circuit position. This allows the full insulating strength between the electrodes 2 and 3 to be maintained without impairment by reason of the presence of the mercury 10 within the container.

I desire, therefore, that my invention be considered in its broad aspects and limited only by the showing of the prior art and by the scope of the appended claims.

What I claim as new and desire to secure by Letters Patent of the U. S. is:—

1. A tiltable electrical contactor for electric power circuits comprising an hermetically sealed tubular glass container, spaced electrodes formed of a substantially pure metal of the iron group disposed therein at one end thereof, leading-in wires of substantial current carrying capacity for said electrodes that are permanently hermetically sealed in said glass container, a freely movable meniscus of mercury riding on the inner surface of said container and adapted to

bridge said electrodes when said container is tilted to a predetermined angle, and an atmosphere of hydrogen within said container.

2. An electrical contactor device for electric power circuits and possessing a commercially useful life, comprising an hermetically sealed container, a freely movable meniscus of mercury therein, substantially pure iron electrodes of substantial concentrated mass 10 and surface area disposed in said container, leading-in wires of substantial current carrying capacity for said electrodes hermetically and permanently sealed in the walls of said container, said leading-in wires being 15 embedded in inert material to preclude their exposure within said container, and an atmosphere of hydrogen gas filling said container whereby said electrodes become wetted with adhering films of mercury when 20 an electric current is made and broken between said electrodes and said body of mercury, said adhering films serving as the contact making area of the electrodes.
3. An electrical contactor device for electric power circuits and possessing a commercially useful life, comprising an hermetically sealed container, a freely movable meniscus of mercury therein, electrodes composed of metal of the iron group disposed in said 30 container, and an atmosphere of hydrogen in said container, the material composing the electrodes co-acting with the said gaseous filling in the presence of electric arcs to form adhering mercury films on the conducting 35 surfaces of said electrodes whereby the electric current makes-and-breaks are established between said body of mercury and said adhering mercury films.
4. An electrical contactor device for electric power circuits and possessing a commercially useful life comprising an hermetically sealed container, a freely movable meniscus of mercury therein, electrodes composed of metal of the iron group disposed therein, relatively thin leading-in wires of substantial current carrying capacity for said electrodes and forming permanent hermetical seals in the walls of said container, said leading-in wires being protected from exposure within 45 said container, and a gaseous filling of hydrogen for said container, the material composing said electrodes coacting with said gaseous filling whereby, in the presence of electric arcs established at said electrodes, 50 adhering films of mercury are formed on the contacting surfaces of said electrodes, said adhering films serving as the active portions of said electrodes.
5. An electrical contactor device for electric power circuits and possessing a commercially useful life comprising an hermetically sealed container, a freely movable meniscus of mercury therein, an atmosphere of hydrogen filling said container, spaced iron electrodes disposed at one end in said container 55 that becomes wetted by the said mercury in the presence of said hydrogen atmosphere whereby films of mercury adhere to said electrodes and serve as the active contact making areas of said electrodes, and relatively thin 70 leading-in wires of substantial current carrying capacity for said electrodes and forming permanently hermetical seals in the walls of said container.
6. In a contactor device for electric power 75 circuits and possessing a commercially useful life, the combination with an hermetically sealed container, of iron electrodes disposed therein, a freely movable meniscus of mercury in said container serving to make 80 and break an electric circuit between said electrodes, and a gaseous filling comprising hydrogen for the container, said filling co-acting with said electrodes to form upon their contacting surfaces adhering mercury 85 films whereby said electrodes are precluded from deteriorating when handling electric currents of higher values than similar electrodes in the absence of such a gaseous filling are capable of handling without undergoing deterioration.
7. A mercury electric switch comprising a tubular glass container that is hermetically sealed and from which atmospheric air has been substantially exhausted, an atmosphere 90 comprising hydrogen filling said container, adjacent cooperating electrodes located centrally of the axis of the tubular container and at one end thereof, each of said electrodes being made of substantially pure iron, having a substantial concentrated mass and an exposed contact-making surface of large 95 expanse, leading-in wires of substantial current-carrying capacity severally connected to said electrodes and forming permanently 100 hermetic seals in the wall of said glass container and serving as means for conducting electric current to said electrodes, each leading-in wire being covered with inert material to preclude its exposure within the said 105 glass container, and a freely movable meniscus of mercury riding with minimum frictional resistance on the inner surface of said tubular glass container whereby the electric circuit through the switch may be made and 110 broken at said electrodes by tilting the switch through a minimum angle, said meniscus of mercury occupying a position remote from the electrodes when the switch is 115 in open circuit position.
8. A mercury electric switch comprising a tubular glass container that is hermetically sealed, cooperating electrodes of substantial concentrated mass and contact-making area 120 located centrally of the axis of said container, a freely movable meniscus of mercury riding unobstructedly on the lower inner surface of said container whereby the electric circuit may be made and broken at said electrodes by said mercury meniscus, one of 125 130

- said electrodes being rounded and projecting vertically downwardly into said mercury meniscus when it occupies circuit-closing position, and leading-in wires severally sealed in the wall of said container and connected to said electrodes, the leading-in wire for said vertical electrode being surrounded with a glass shank integral with the wall of said container and abutting said electrode to preclude exposure of said leading-in wire within the container and the leading-in wire for the other electrode being embedded in inert material to preclude its exposure within said container.
10. 9. In an electrical contactor device for electric power circuits, a sealed container, electrodes positioned within said container, an atmosphere comprising hydrogen gas filling said container, and a body of mercury movable to make and break the circuit between said electrodes, the latter being composed of a metal that is substantially non-amalgamating with said mercury, upon the passage of an electric arc, said device being substantially non-deteriorating by reason of the inter-action of the mercury, said atmosphere and said metal electrodes.
10. In an electrical contactor device, a sealed container, iron electrodes positioned therein, an atmosphere comprising hydrogen gas filling said container, and a body of mercury movable to make and break the circuit between said electrodes, the action of said atmosphere and iron being such that the electrodes are substantially non-deteriorating upon the passage of an electric arc.
11. An electrical contactor comprising an elongated hermetically sealed container of insulating material, a quantity of mercury in said container adapted to ride back and forth on the inner surface of the container and lengthwise thereof when the container is tilted in opposite directions past a horizontal position, electrical conductors composed of metal of the iron group within the container in position to cooperate with the mercury to open and close the electric circuit through said contactor upon the tilting of the latter, and an atmosphere of hydrogen in the container, the action of the said atmosphere, the mercury and said electrical conductors being such that the contactor is substantially non-deteriorating.
12. An electrical contactor comprising an elongated hermetically sealed container, a quantity of mercury in said container adapted to ride back and forth on the inner surface of the container and lengthwise thereof when the container is tilted in opposite directions past a horizontal position, leading-in wires extending through the wall of said container and being of a material to provide substantially permanent hermetic seals therein, electrical conductors comprising a metal of the iron group at the inner ends of said leading-in wires and being positioned to cooperate with the mercury to open and close the electric circuit through the contactor upon tilting it, and an atmosphere comprising hydrogen filling the said container.
13. An electrical contactor comprising a hermetically sealed container, electrical conductors hermetically sealed in said container and severally terminating into an exposed portion within the container that is composed of a metal of the iron group, said exposed portions cooperating with the mercury to open and close the electric circuit through said contactor when tilted, an atmosphere comprising hydrogen gas filling said container, a quantity of mercury contained within said container and which contacts with said electrical conductors to open and close the electric circuit through said contactor, the action of said atmosphere, the mercury and said electrical conductors being such that the contactor is substantially non-deteriorating.

In witness whereof, I have hereunto subscribed my name.

LOUIS A. M. PHELAN.

- said electrodes being rounded and projecting vertically downwardly into said mercury meniscus when it occupies circuit-closing position, and leading-in wires severally sealed in the wall of said container and connected to said electrodes, the leading-in wire for said vertical electrode being surrounded with a glass shank integral with the wall of said container and abutting said electrode to preclude exposure of said leading-in wire within the container and the leading-in wire for the other electrode being embedded in inert material to preclude its exposure within said container.
15. 9. In an electrical contactor device for electric power circuits, a sealed container, electrodes positioned within said container, an atmosphere comprising hydrogen gas filling said container, and a body of mercury movable to make and break the circuit between said electrodes, the latter being composed of a metal that is substantially non-amalgamating with said mercury, upon the passage of an electric arc, said device being substantially non-deteriorating by reason of the inter-action of the mercury, said atmosphere and said metal electrodes.
10. In an electrical contactor device, a sealed container, iron electrodes positioned therein, an atmosphere comprising hydrogen gas filling said container, and a body of mercury movable to make and break the circuit between said electrodes, the action of said atmosphere and iron being such that the electrodes are substantially non-deteriorating upon the passage of an electric arc.
11. An electrical contactor comprising an elongated hermetically sealed container of insulating material, a quantity of mercury in said container adapted to ride back and forth on the inner surface of the container and lengthwise thereof when the container is tilted in opposite directions past a horizontal position, electrical conductors composed of metal of the iron group within the container in position to cooperate with the mercury to open and close the electric circuit through said contactor upon the tilting of the latter, and an atmosphere of hydrogen in the container, the action of the said atmosphere, the mercury and said electrical conductors being such that the contactor is substantially non-deteriorating.
12. An electrical contactor comprising an elongated hermetically sealed container, a quantity of mercury in said container adapted to ride back and forth on the inner surface of the container and lengthwise thereof when the container is tilted in opposite directions past a horizontal position, leading-in wires extending through the wall of said container and being of a material to provide substantially permanent hermetic seals therein, electrical conductors comprising a metal of the iron group at the inner ends of said leading-in wires and being positioned to operate with the mercury to open and close the electric circuit through the contactor upon tilting it, and an atmosphere comprising hydrogen filling the said container.
13. An electrical contactor comprising a hermetically sealed container, electrical conductors hermetically sealed in said container and severally terminating into an exposed portion within the container that is composed of a metal of the iron group, said exposed portions cooperating with the mercury to open and close the electric circuit through said contactor when tilted, an atmosphere comprising hydrogen gas filling said container, a quantity of mercury contained within said container and which contacts with said electrical conductors to open and close the electric circuit through said contactor, the action of said atmosphere, the mercury and said electrical conductors being such that the contactor is substantially non-deteriorating.

In witness whereof, I have hereunto subscribed my name.

LOUIS A. M. PHELAN.

Certificate of Correction.

It is hereby certified that in Letters Patent No. 1,598,874, granted September 7, 1926, upon the application of Louis A. M. Phelan, of Beloit, Wisconsin, for an improvement in "Electrical Apparatus," errors appear in the printed specification requiring correction as follows: Page 4, lines 17 and 18, strike out the words "other materials which are exposed thereto" and insert instead the words *iron electrodes or the mercury or the glass should be inserted in lieu thereof*; page 5, line 68, for the word "occupied" read *occupies*; and that the said Letters Patent should be read with these corrections therein that the same may conform to the record of the case in the Patent Office.

Signed and sealed this 2d day of November, A. D. 1926.

[SEAL.]

WM. A. KINNAN,
Acting Commissioner of Patents.

DISCLAIMER

1,598,874.—*Louis A. M. Phelan*, Beloit, Wis. ELECTRICAL APPARATUS. Patent dated September 7, 1926. Disclaimer filed May 29, 1936, by the assignee of one-half interest, *Minneapolis-Honeywell Regulator Company*.

Hereby disclaims, to the extent solely and only of the one-half interest possessed by it, claims 9, 11, 12, and 13.

[*Official Gazette October 20, 1936.*]

DISCLAIMER

1,598,874.—*Louis A. M. Phelan*, Beloit, Wis. ELECTRICAL APPARATUS. Patent dated September 7, 1926. Disclaimer filed February 26, 1937, by the assignee of one-half interest, *Arcless Contact Company*.

Hereby enters this disclaimer to the extent solely and only of its undivided one-half part of the whole right, title and interest possessed by it to claims 9, 11, 12, and 13 in said specification.

[*Official Gazette March 30, 1937.*]
